UNITED STATES PATENT OFFICE.

HERBERT ALFRED STAUB, OF BADEN-BADEN, GERMANY.

DESIGN FOR A HAND ORNAMENT.

Application filed January 20, 1925. Serial No. 12,093. Term of patent 7 years.

To all whom it may concern:

Be it known that I, HERBERT ALFRED STAUB, a citizen of the German Republic, residing at the city of Baden-Baden, Germany, have invented a new, original, and ornamental Design for a Hand Ornament, of which the following is a specification, reference being had to the accompanying drawing, forming part thereof.

The outer side of the hand ornament is shown in Fig. 1 applied to the back of the hand of the wearer which hand is illustrated in dotted lines, and Figure 2 shows the reverse side thereof.

I claim:

The ornamental design for a hand-ornament, as shown.

DR. HERBERT ALFRED STAUB.
